DISTRIBUTING CARRIER FOR MAIL AND
THE LIKE

Thomas W. Savage, Reading, Mass.

Application February 13, 1935, Serial No. 6,407

2 Claims. (Cl. 312—62)

My invention is concerned with the carrying and distributing of postal matter and the like, such as letters, cards and similar articles, and more particularly aims to provide a readily trans-
5 portable carrier, rack or magazine adapted for detachable mounting in convenient location, and especially adapted for use by mail carriers on rural free delivery routes, in making deliveries from an automobile.

10 In the drawing illustrating by way of example one embodiment of my invention,

Fig. 1 is a plan of the receptacle, carrier or magazine, as in use;

Fig. 2 is a front elevation of the same;

15 Fig. 3 is a right end elevation with a portion broken away to illustrate an adjustable supporting means; and

Fig. 4 is a section on the line 4—4 of Fig. 1.

The device as shown for the purposes of illustration, and hereinafter referred to as a rack, carrier or magazine, comprises a main frame, housing or receptacle indicated as a whole by the numeral 5. It is of open-front and open-top construction, herein including a rear wall 6, 25 and end walls 7 and 8, these walls enclosing and supporting a floor or base 9. Sheet metal or other suitable constructions may be employed in forming the rack. The open compartment defined by the vertical walls and the floor 9 is of 30 a height and length to accommodate pieces of first class mail matter of ordinary sizes, up to ten or twelve inches in length, for example, and has a depth adequate to receive a batch or group of such articles.

35 The general practice with rural postal carriers is to sort and bundle the mail matter into bundles or packages averaging some 40 to 50 pieces, depending on their thickness, making up a bundle some two to three inches thick or thereabouts, 40 the pieces being held together by a surrounding leather or other strap. The individual pieces are arranged in order for delivery along the particular route. These bundles are generally placed on the seat of the automobile beside the carrier, 45 who usually must also act as the driver of the car. In making a delivery stop it is thus necessary for the carrier to take both hands from the steering wheel, and to grasp the strapped bundle of letters or mail pieces with one hand 50 while withdrawing with the other hand the particular piece or pieces of mail for deposit in the rural delivery box at the given address. The strap enclosing the bundle when tight enough to hold the letters, interferes with their quick 55 withdrawal. It also requires frequent time-con-

suming adjustment, as the bundle becomes depleted, to prevent the remaining letters from becoming so loose as to slip from the strap.

My invention contemplates a device or means whereby the batch of sorted mail matter may be held and carried in visible position conveniently accessible to the carrier and in such fashion that a selected piece may readily be withdrawn and delivered, by the use of but one hand by the carrier. Accordingly the described receptacle, 10 rack or magazine 5 is provided with means for detachably supporting it in fixed position conveniently at hand to the carrier as he drives his automobile. In the form illustrated I provide one or more supporting elements or hangers 10, 15 10, two being here illustrated. These include hook portion 11 adapted to be engaged over the top edge of an automobile door D, or upon the dash board or other convenient support, and an adjustable attaching portion 12 having means 20 such as the slot 13 for receiving a bolt 14 on the rear wall of the rack 5. The supports 10 are thus vertically adjustable, to accommodate the rack to different door structures or other points of attachment. The hook portions of the 25 supports or hangers 10 may be rubber covered for protective purposes as indicated at 11a, Fig. 3. The rear wall of the rack may also have one or more rubber or other buttons or nubbins 15, Fig. 3, for contact with the face of the door or other 30 support, to assist in positioning the rack and preventing marring.

It will be understood that the batch or collection of letters—under which term I intend to include any pieces of mail matter and the like 35 which are to be distributed—is placed in upright position within the compartment of the rack or magazine, facing outwardly toward the open front. Further in accordance with the invention, means, preferably automatic or self-adjusting, is provided for retaining the letters in carrying position, and in such fashion that the face of the outer piece or letter is not obscured to any objectionable extent but is left fully visible, with any legends such as names and addresses in full 45 view. At the same time the letters are so positioned and presented that the outer one or any selected letter or plurality of them may be quickly picked from the batch and withdrawn, by the use of but a single hand. 50

Herein for the purpose I have illustrated a holding or clamping device operatively located within the compartment. Referring to Figs. 1, 2, and 4, it is shown as including a swinging arm 16 of open construction, having upper and lower horizontal 55

parts 17 and an upright connecting part 18, formed of wire or other suitable material. As shown, one of the horizontal parts, herein the lower one, is extended at right angles vertically to provide 5 a pivot 19 for the arm, the upper end of the pivot being received in an eye or like formation 20 in the upper part 17. The pivot 19 extends through suitable bearings or apertures in the spaced ears 21, 21 of a bracket 22 at the inner face of one of the walls, herein the end wall 7. A coil spring 23 surrounds the pivot 19, one end of the spring being held as at 24 and the other end being extended as at 25 across one of the horizontal parts 17 of the arm, urging the latter inwardly, toward 10 the back of the compartment.

This swinging clamp arm appears in full lines in Fig. 1 in its rearmost position, as when the rack is empty, and in dotted lines in an intermediate position, as when holding a batch of letters, the 15 latter being indicated in broken lines at L.

As deliveries are made from the batch of letters the angular relation between the arm 16 and the face of the outer letter varies. In order that the letters may be securely held irrespective of 20 their number, within the total capacity of the rack, I preferably provide a self-adjusting engaging element, foot or clamp proper indicated as a whole by the numeral 26. As shown, this element comprises an open frame, affording the maximum of visibility to the face of the engaged letters. This frame or presser foot 26 may conveniently be fashioned of wire bent to form a flat engaging element such as illustrated by way of example, and herein including top and bottom portions 26^a, 25 side members 26^b and upper and lower substantially centrally disposed loops or eyes 27 pivotally received upon the upright or connecting part 18 of the pivoted arm 16. The horizontal parts 17 of the latter serve to position the foot 26 vertically. 30 Thus the engaging foot is adapted to swivel or turn with respect to the spring-pressed arm 16, automatically, so that it may remain always in parallelism with itself and in complete flatwise engagement with the face of the then outermost letter, whether the compartment or magazine of 35 the rack be completely filled or in various stages of its depletion, even down to a single remaining article. It will also be seen that in the illustrated arrangement the holding means at all times leaves 40 substantially the entire right half of the compartment entirely free for access to the letters, so that the selected one or plurality may be readily engaged or withdrawn through the open top and front of the rack, while due to the open structure 45 of the engaging element or foot 26 and of its supporting arm 16 substantially the entire face of an outer letter is freely visible at all times.

The main frame or housing of the carrier or rack may be integrally or otherwise constructed 50 of sheet metal or other suitable material. The device as a unitary whole desirably also presents means for conveniently storing and carrying stamps, cards, stamped envelopes, cash, or other

articles likely to be required by a rural carrier in the course of his duties, or by any user of the device. To this end the vertical walls of the letter compartment are extended downwardly, as seen in Figs. 2 to 4 and are inturned as at 28, 28 to 5 form supports and guides for a drawer 29, for which the floor 9 of the letter compartment provides a cover. Suitable means desirably is provided for operating the drawer and herein for holding it in closed position. As illustrated, this means comprises a knob 30 on a stud 31 extending rotatably through the front wall of the drawer 29, and through a spacing washer 31. An eccentric or finger 32 is fixed at the inner end of the stud 31, in position to be engaged behind a stop 33 depending from the floor 9. By turning the knob 30, to engage or disengage the eccentric 32 with respect to the stop, the drawer may readily be locked or released.

My invention is not limited to the particular 20 illustrative embodiment herein shown and described, its scope being set forth in the appended claims.

I claim:

1. A mail rack particularly for use by rural carriers in transporting and delivering mail along their routes, said rack comprising a single compact main receptacle of a size adapted to the convenient reception and positioning of a batch of pieces of mail such as customarily strapped up in 30 a single bundle by such rural carriers, said receptacle having integral sheet-metal vertical side and rear walls of a height not substantially exceeding that of the mail pieces and being wholly and permanently open at the front and top, a horizontal 35 flat and unobstructed sheet-metal bottom wall carried by said vertical walls, a vertically disposed presser member swiveled for self-paralleling flatwise clamping contact against the upright forwardly facing addressed face of the outer piece of 40 mail irrespective of the distance of the latter from the rear wall of the receptacle, a swinging arm pivotally supported on a wall of the receptacle and carrying said swiveled presser member, spring means urging said arm and presser member inwardly, said presser member and its supporting means being of such open structure as to leave the vertical front face of the engaged mail piece substantially unobscured and cooperating with the vertical walls of the receptacle to present the letters for successive withdrawal in an upward and forward direction, and attaching means for readily detachably supporting said mail rack as a whole in convenient fixed position upon the letter carrier's vehicle.

2. A mail rack in accordance with claim 1, wherein the vertical sheet-metal walls of the main receptacle are integrally continued downwardly below the bottom wall and are horizontally in-turned at their bottom edges to form a one-piece 55 supporting and guiding means for a drawer.

THOMAS W. SAVAGE.
